UNITED STATES PATENT OFFICE.

THOMAS E. JORDAN, OF WAKEFIELD, MASSACHUSETTS.

SHOE-POLISHING CABINET.

Application filed February 14, 1923. Serial No. 619,032.

This invention relates to a shoe-polishing cabinet and has for its object to provide a novel box or container for receiving the shoe-polishing appliances which is designed 5 to be pivotally supported from a wall in such a way that when not in use it may be folded back against the wall and when it is to be used it may be swung outwardly into a position to constitute a foot rest to support the foot as the shoe is being shined.

Another object of the invention is to provide an improved shoe-polishing appliance in which the box or casing is provided with an open side so that the shoe-polishing appliances therein are readily accessible and which is so supported by the wall that when the box is folded against the latter the open side thereof is closed by the wall.

A further object of the invention is to 20 provide means for locking the box in either its folded position against the wall or when in position to be used as a support for the foot.

A further object of the invention is to 25 provide a novel device of this type which operates to support the foot in such a way that the latter can be freely rocked or turned into different angles as necessary and desirable to make it convenient for a person to reach different portions of the shoe in polishing the latter.

In order to give an understanding of the invention I have illustrated in the drawings a selected embodiment thereof which will 35 now be described after which the novel features will be pointed out in the appended claims.

Fig. 1 is perspective view of a device embodying my invention showing it in full 40 lines folded against the wall and in dotted lines in operative position for use;

Fig. 2 is a longitudinal vertical section of one embodiment of the invention;

Fig. 3 is a similar sectional view showing 45 a different embodiment of the invention;

Fig. 4 is a section on the line 4—4, Fig. 1;

Fig. 5 is a fragmentary perspective view of the upper portion of the pivotal support for the container shown in Fig. 3.

As stated above the device comprises a box 50 or container having an open side and adapted to contain the shoe-polishing implements

and means for pivotally supporting said box to a wall in such a way that it can be swung about a vertical axis so that it may be folded 55 against the wall or swung out into position to constitute a support for the foot. When it is in folded position the open side thereof is closed against the wall so that the latter forms a closure for said open side. The 60 means for supporting the box or container is strong enough so that when said box is swung away from the wall it may function as a support for the foot and the foot-supporting portion of the box is constructed to 65 permit the foot to have a free rocking movement so as to allow it to be turned into different positions as necessary to facilitate access to different portions of the shoe.

The box or container may be either made 70 of metal or of wood as found most desirable. In Figs. 1, 2 and 4 I have shown a construction in which the box is made of sheet metal and in Fig. 3 a construction in which the box is made of wood. Referring first to 75 Figs. 1 and 4 the box or container is shown at 1 and it is provided with the open side. Said box will preferably have such a shape that the transverse dimension from the open side to the opposite closed side will be very 80 much less than either of the other two dimensions. Such a box will be much narrower than the height or the length thereof. The box or container is pivotally secured to a wall 2 to turn about a vertical axis situated at one end of the box and in such a way that the box may be folded against the wall with the open side toward the wall. Various ways of thus securing the box to the wall 2 may be employed without departing 85 from the invention.

In the construction herein shown I provide a holder or support 3 which is secured to the wall 2 and is formed with laterally-extending arms 4 to which the box is pivoted. In the case of a sheet metal box I will preferably connect the box to the holder 3 through a box-supporting member 5 herein shown as a U-shaped member adapted to embrace the box. The upper arm 6 of this member 5 extends underneath the top 7 of the box and through openings 8 in the ends thereof and the lower leg 9 of said member extends underneath the box, the connecting 95 100

portion 10 extending down the outside of the box end 11. This supporting member 5 may be secured to the box in any suitable way as by means of screws or bolts 12. The ends 5 of the supporting member extend beyond the inner end 14 of the box and are pivotally connected to the holder 3. This is accomplished by employing a journal member 15 which extends through the ends 13 of the 10 member 5 and constitutes a pivotal bearing therefor. The position of this journal member 15 is such relative to the thickness of the box that when the latter is swung into position parallel with the wall 2 as 15 shown in Fig. 1 the open side of the box will be brought against the wall so that the latter forms a closure for the open side. The box can also be swung into a position at right angles to the wall as shown in 20 dotted lines Fig. 1.

The journal member 15 is constructed so that it operates to lock the box in either of these positions. Said member is shown as fixed in the arms 4 and as having portions 25 16 at the top and bottom thereof which are non-circular in cross section and other portions 17 adjacent the non-circular portions 16 which are circular in cross section. The apertures 18 through the ends 13 are non- 30 circular and of a shape to fit the non-circular portions 16 of the member 15. The circular portions 17 are situated above the non-circular portions and the length of the member 15 is such as to permit the box- 35 supporting member 9 to have a slight upward movement.

When the parts are in the position shown in Fig. 1 the non-circular portions 16 occupy the apertures 18 thus locking the box from swinging movement. If the box is 40 raised slightly on the member 15 then the circular portions 17 come into the apertures 18 thus permitting the box to be turned and when it has been brought into the dotted line position Fig. 1 then it may be lowered again to bring the non-circular portions 16 into the apertures thus locking the box in 45 its open position. When in this position the box stands at right angles to the wall 2 and at the corner 19 thereof is provided a 50 stirrup adapted to receive the arch of the foot and form a support therefor as the shoe is shined. This stirrup is in the form of a plate 21 which is secured to the box 55 at the corner and which is provided with guide lips 20 to prevent the shoe from slipping sidewise. This foot support is intended to support the arch of the foot only, the 60 heel of the foot projecting beyond the box and being unsupported. A shoe support of this nature has advantages because it permits the operator to rock his foot up and down about the corner of the box, this resulting from the fact that the heel is 65 unsupported.

If desired the box may be provided with a shelf 22 thus dividing it into compartments 1, although this is not essential.

In Fig. 3 I have illustrated a little different construction in which the box is of 70 wood and is intended to be strong enough to support the foot without requiring to be stiffened or strengthened by the box-supporting member 5. Such a box is indicated at 23 and it may have substantially the 75 same dimensions as that shown in Fig. 1.

The box has secured to its inner end a supporting member 24 which is shown as having arms 25 that overlie the top and bottom 80 of the box and are secured thereto by suitable screws 26 and also having trunnions which are journalled in the arms 4 of the box holder 3.

Each trunnion is provided with a cylindrical portion 29 and a non-cylindrical portion 30 directly above the cylindrical portion. The arms 4 of the holder are provided with non-circular openings 31 which fit the non-cylindrical portions 30 of the 85 trunnions. 90

The box will normally be held by gravity in its lower position shown in Fig. 3 with the non-circular portions 30 occupying the openings 31 thus locking the box from turning movement. By raising the box slightly the cylindrical portions 29 are brought into the aperture thus permitting the box to be freely turned and, therefore, this construction provides means for pivotally supporting the box so that it may be swung against 95 the door or outwardly into a position at right angles thereto and by which the box 100 may be locked in either of these two positions.

While I have illustrated some selected embodiments of my invention I do not wish to be limited to the constructional features shown. 105

I claim:

1. In a shoe-polishing device, the combination with a box open on one side and adapted to contain shoe-polishing implements, of means for pivotally supporting the box from a wall so that it can be turned about a vertical axis and swung either into an inoperative position parallel to the wall with the open side against the wall or into an operative position at right angles to the wall, and means associated with the pivot for the box to lock said box in either position, the corner of the box, when the latter is in operative position, providing a support for the arch of the foot. 110

2. In a device of the class described, the combination with a box open on one side and adapted to contain shoe-polishing implements, of a box holder secured to a wall, means for pivotally connecting the box to the box holder to permit said box to swing about a vertical axis from an operative po- 115 120 125 130

sition at right angles to the wall to an in-operative position parallel to the wall and with the open side against the wall, means for locking the box in either of its two positions, the corner of the box providing a support for the arch of the foot and on which it may be freely turned into different

positions when said box is in operative position, and guard lips at said corner of the box to prevent the foot from slipping sideways.

In testimony whereof, I have signed my name to this specification.

THOMAS E. JORDAN.
